UNITED STATES PATENT OFFICE.

HARRY BERMAN, OF BROOKLYN, NEW YORK.

AUTOMATIC SASH-LOCK.

1,272,900.

Specification of Letters Patent. Patented July 16, 1918.

Application filed April 19, 1917. Serial No. 163,235.

To all whom it may concern:

Be it known that I, HARRY BERMAN, a citizen of the United States, residing at Brooklyn, in the county of Kings and State of New York, have invented certain new and useful Improvements in Automatic Sash-Locks, of which the following is a specification.

The primary aim of this invention is to provide a simply and durably constructed sash lock which will become automatically operative on movement of the sash or sashes of a window, and it consists in a keeper mounted on one sash and a spring projected latch that is releasably supported in an inoperative position to be engaged, during movement of the sash by an obstruction or trip for releasing and allowing the latch to move to an operative position.

10 The invention further resides in an automatic sash lock which may be manually operated to lock the sashes in various partially-open positions for ventilation.

20

In the drawing:—

25 Figure 1 is a fragmentary perspective view of a window embodying the present invention and depicting the latter in an inoperative position about to be automatically tripped or released for movement to an operative position.

Fig. 2 is a vertical sectional view showing the sash lock inoperative in full lines and operative in dotted lines, and

30 Fig. 3 is a horizontal section of the sash lock in inoperative position.

Referring more in detail to the drawing and using similar numerals of reference for corresponding parts throughout the several views, 1 designates the window frame having the upper sash 2 and the lower sash 3 arranged therein for vertical sliding.

40 In the inner face of the upper sash and at one side thereof is secured a flat catch plate 4 having a vertical series of openings 5, the upper walls 6 of which are straight while the lower walls 7 are preferably curved downwardly.

On the top of the lower sash is secured a casing 8 having perforated base flanges 9 through which the securing screws 10 are passed. This casing is formed with a latch chamber 11 which has its forward end open and its rear end closed by an end wall 12. A latch bolt 13 has its forward end beveled 55 underneath, as at 14, and is slidably disposed in the casing chamber, a stem 15 being car-

ried by the bolt and guided through the end wall 12. A coiled spring 16 encircles the stem 15 between said end wall and the shoulder 17, formed by said latch bolt, for urging 60 the latter to a projected position.

Rotatably mounted on the free outer end of the stem is a winged head 18 and extending from the opposite sides of the wall 12 in parallel relation is a pair of arms or supports 19 on the outer ends of which the head 18 is adapted to rest, when the latch is retracted, for retaining the latter inoperative. Should the head be rotated to disengage its wings from the arms 19 the coiled 70 spring will project the latch and move the head between said arms as illustrated by dotted lines in Fig. 2.

Obviously this rotation of the head may be manually accomplished, and such is the 75 preferred operation for locking the sashes partially opened, but to positively insure a locking of the sashes when they are closed, the turning of the head is effected automatically by a trip pin or screw 20 that is arranged on the frame in the path of the head 18 when the latter is engaged with the arms. This pin is disposed on the frame slightly above the normal position of the head so as to engage and release the latter immediately 80 before the window is closed. Consequently while the head is supported by said arms 19, the sashes may be raised and lowered without springing the lock. However, as the lower sash approaches its limit of closing movement the trip pin rotates the head from off the arms to permit the coiled spring 16 projecting the lock into engagement with the catch plate. Thus, when the window is closed the sashes are automatically locked by 95 a device so arranged as to be inaccessible from outside the window. It is apparent that the element 20 may be arranged in different relative positions so as to cause the release of the latch at the desired time and 100 either in the opening or closing movement of the sash.

While the foregoing description has been very minute, it is understood that in the manufacture of the device such practical 105 changes may be resorted to as fall within the scope of the appended claims.

Having thus described my invention, what I claim as new is:—

A window sash lock, comprising a casing 110 closed at its rear end, a spring actuated bolt mounted therein and having a portion pro-

jecting through the rear end of the casing, a head loosely mounted on the rear extremity of the projecting portion of the bolt for rotation, the sides of the casing having integral extensions forming spaced arms with the ends of which the rotatable head is engageable to hold the bolt retracted in the casing, and relatively stationary means

adapted to be impinged upon movement of the sash to turn the head relatively to the bolt to disengage the head from the arms whereby the bolt may move into locking position.

In testimony whereof I affix my signature.

HARRY BERMAN. [L. s.]
